B. GOODMAN

DRAFT REGULATOR

Filed Feb. 13, 1926

UNITED STATES PATENT OFFICE.

BARNEY GOODMAN, OF CHICAGO, ILLINOIS.

DRAFT REGULATOR.

Application filed February 13, 1926. Serial No. 88,032.

This invention relates to draft regulators, and more particularly to automatic regulators for heating boilers.

It contemplates more especially the provision of simple means which will afford automatic regulation over a wide operating range thereby effecting a marked economy of fuel without necessitating the use of a thermostat or other complex and expensive expedients.

10 The regulators of known construction are expensive, complex in structure, and ineffective over a wide operating range. Boilers and other heat generating systems are operated at extreme loads which necessarily subjects them to high and low pressures, thereby necessitating the use of regulators which are adapted to function under extreme conditions without impairing their sensitivity and reliability.

20 Further, since it is usual practice for generating systems to produce loads of varying capacity, it is desirable that their regulators be readily adjustable to effect economic regulation at the desired pressure or pressures.

25 One object of the present invention is to improve the construction and operation of devices of the character mentioned.

Another object is to provide an inexpensive device which is effective to render automatic regulation over a wide operating range.

30 Still another object is to provide simple means for varying the range of operation of regulators with ease and accuracy.

35 A further object is to provide a regulator which is sensitive to heat changes, thereby insuring economic fuel consumption and efficient operation at any predetermined load.

40 A still further object is the provision of an automatic regulator which does not necessitate the use of a thermostat or other complicated and expensive expedient.

45 Other objects and advantages will appear from the following description of an illustrative embodiment of the present invention.

In the drawings:

Figure 1 is a perspective view of a steam boiler and a regulator therefor.

Figure 2 is a view of the flue closure and its associated parts.

50 Figure 3 is a fragmentary sectional view showing a regulator embodying features of the present invention.

55 A regulator illustrative of the present invention is shown applied to an ordinary steam boiler 10 having the usual hinged, gravity operated draft door 11 which controls the

admission of air to the fire box, and the usual hinged draft closure 12 which controls the intake of air to the flue 13 through which the waste flue gases escape to the atmosphere. 60

Steam pressure in the boiler 10 communicates with a steam cylinder 14 which in this instance, is vertically disposed and mounted so that its lower or steam end is subjected to the pressure in the valved steam line 15. Secured to the cylinder 14 is a cylinder head 16 which is in threaded engagement therewith through the usual nipple 17. As shown, the cup shaped cylinder head 16 is threaded to the cylinder 14 in the usual manner. A piston 18 is mounted for reciprocation in the cylinder 14 so that the centrally disposed piston rod 19 secured thereto will impart movement to a lever 20, which contacts therewith and moves upwardly as a result of a pressure 75 change. In order to insure proper piston reciprocation without jamming or causing unusual wear of the coacting parts, a cylinder head 21 having a central upstanding boss 22 provided with a bore 23 to receive the piston 80 rod 19 forms a long guide therefor. This is highly desirable, for the piston is then incapable of tilting, thereby insuring smooth piston reciprocation within the cylinder 14 at all times. To enable the air confined in 85 the cylinder above the piston rod 19 to escape upon upward movement of the piston, the cylinder head 21 is provided with one or more perforations 24 which freely permits ingress and egress of the air to and from the variable 90 space above the piston thereby subjecting it to atmospheric pressure.

A bell crank 20 is pivoted about the shaft 25 which is mounted in a fork 26. The fork is rigidly secured in fixed relation to the cylinder 14 by virtue of a horizontally disposed plate 27 which is provided with a hole 28 at one end thereof to fit over the boss 22. The boss is externally threaded at 29 to receive a lock nut 30 which firmly holds the plate 27 100 against the cylinder head 21. A standard 31 which is secured to the fork 26 in any appropriate manner as by the cap screw 32 renders the lever 20 vertically adjustable, in that the lower portion of the standard 31 is 105 threaded as at 33 to receive a pair of spaced nuts 34 and 35 between which the plate 27 is firmly fixed by virtue of the opening provided therein. Obviously by manipulating the nuts 34 and 35 the extension rod 31 may 110 be raised or lowered within the limits of the threaded portion 33.

The piston rod 19, as shown, is adapted to coact with the lever 20 to impart movement thereto about the pivot pin or shaft 25. The upper extremity of the rod 19 is provided with a bifurcated end connection 36 which is adapted to receive the lever 20 between said bifurcations. A roller 37 is rotatively mounted within and between the bifurcations on a transverse pivot pin 38 so that as the roller 37 contacts with the lever arm 20 to impart movement thereto, the roller 37 will be caused to rotate, thereby eliminating friction resulting from a sliding contact. It is to be noted that the lever 20 will be caused to rotate about its shaft 25 in a clockwise direction upon upward movement of the piston rod 19; however, a downward movement of the rod 19 will not affect the movement of the lever 20 thereby necessitating the use of means to normally keep the lever arm in its lowest position. The method employed in the present embodiment consists of gravity operated means to be hereinafter described.

It is one purpose of this invention to regulate the alternate admission of air to either the fire box or the chimney flue. Therefore it is possible to directly connect the draft door which controls admission to the fire box, and the flue closure in such a way as to effect their simultaneous opening and closing or vice versa as may be necessary to regulate the pressure of the system within predetermined limits. The means employed in the present instance to effect such simultaneous movement of the flue and fire box draft doors, comprise flexible tension transmitting means, in this instance a chain 39 which connects the fire box draft door 11 and the parts associated with the lever 20. Likewise the flue draft door 12 is connected to the lever by similar means such as the chain 40 and 41 which are interconnected by virtue of an inverted T-shaped lever 42 which is pivoted to a fixed vertical standard 43 preferably at the jointure of its arms 44, 45 and 46. As shown the standard 43 is situated near and fixed to the frame of the draft door 12 so that the chain 40 may be conveniently connected to an arm 44 of the lever in the usual manner, and the horizontally extended chain 41 connected to the arm 45. It will be noted that any oscillation imparted to the lever 20 by virtue of a pressure change within the cylinder 14 will cause the lever 20 to move in the clockwise direction, thereby closing the fire box door 11 and opening the chimney flue draft door 12. A counter-weight 47 is adjustably secured to the remaining arm 46 of the lever 42 to offset or balance a part of the weight of the draft door 12 which in this instance is of such weight as to effect a constant pull on the lever 20 sufficient to cause it to contact at all times with the roller 37.

With a downward movement of the piston 18

due to a diminishing pressure, the draft door 12 will drop, thereby causing the lever 20 to move in a counter-clockwise direction.

With the arrangement of parts thus far described it is evident that an increase in pressure will open the damper door 12 and close the draft door 11 thereby keeping the boiler in operation under the desired pressure. To enable the closures 11 and 12 to open and close at any desired pressures so as to afford automatic regulation over a wide operating range, means are provided to effect the operation of the regulator over variable predetermined limits thereby making necessary a convenient adjustment so that the heat generating system may be automatically regulated at any desired load or pressure. By so doing the closures 11 and 12 may be made to open and close at any desired boiler pressure or pressures by merely adjusting a simple calibrated means of any desired form which will respond to critical predetermined pressures.

The means for setting the critical pressure at which the air intakes are to open and close to effect regulation, in this instance, comprises a suitably calibrated quadrant which limits the oscillating range of the lever 20, since by adjusting its lowermost counterclockwise position, the piston rod in its movement upward will impart movement to the lever 20 only when the pressure in the system is sufficient to move the end connection 36, which is secured to the extremity of the piston rod 19. The specific means employed in this instance, comprises a quadrant lever 49 having angularly related arms 49^a and 49^b connected by a curved arm 49^c pivoted on the pivot pin 25 at the juncture of the two arms 49^a and 49^b, thereby permitting the quadrant 49 and the lever 20 to move or oscillate about a common center. As shown, the free extremities of the arms 49^a and 49^b of the quadrant 49 are provided with holes 50 and 51 which are designed to receive the extremities of the chains 39 and 41. It will be noted that any movement of the closure 11 will impart a similar movement to the closure 12 by virtue of the direct connection therebetween established by the chains 39, 40 and 41 which are connected to each other through suitable linkage previously described.

In order to retain the lever 20 and the quadrant 49 in fixed relation so that both will move in unison, a detachable yieldable connection is provided between the lever 20 and the quadrant. This connection comprises a pawl 52 mounted in an appropriate guide bracket 53 secured to one arm of the lever 20 by any suitable means such as the fasteners 54. A rod 55 secured to one extremity of the pawl 52 and extending axially therefrom projects through an upstanding guiding lug 56 which is provided with a hole 57 in the face thereof to receive the rod 55 which is adapted to re-

ciprocate with the pawl 52. The other extremity of the pawl 52 is adapted to engage appropriate grooves 58, 59, 60 and 61 provided in the internal peripheral edge of the arch shaped member 49^c of the quadrant 49. As shown, these grooves are arranged at spaced intervals to correspond with pressures ranging from the maximum to the minimum that may be required of the boiler at any time. 10 It is to be noted that this calibration may constitute any desirable indicia that will enable the operator to correctly adjust the lever to engage any portion of the quadrant which denotes a pressure incident to that position. 15 In the present showing, words denoting the severity of the weather are used as a guide in regulating the operation of the heating unit. To normally maintain the pawl 52 in engagement with one of the grooves along the quadrant, a coiled spring 62 mounted on the rod 55 is interposed between the pawl 52 and the guiding lug 56, thereby normally keeping the pawl 52 in engagement with any desired groove. To facilitate the withdrawal of the 20 pawl 52 from its respective groove or notch so as to permit rotation of the lever 20 with respect to the quadrant 46, a suitable handle 63 is secured to the pawl 52 in any appropriate manner so that the latter may be conveniently 25 withdrawn against the resistance of the spring 62.

It will be understood that when the pawl 52 engages the extreme notch 60 designated as "cold", the lever 20, assuming the draft door 35 11 to be open and the maximum desired pressure having been reached, will be rotated in a clockwise direction by a slight upward movement of the piston rod 19 resulting from an increase in pressure. This clockwise rotation of the lever and quadrant, instantly closes the draft door 11 and simultaneously opens the flue draft intake 12 with the result that the fire is checked as would be desirable under this condition.

40 From the above description it will be seen that a regulator has been provided which is simple, positive in action, and readily adjustable to any desired range within which it is desired to regulate a boiler or other heat generating system.

50 Various changes may be made in the embodiment of the invention herein specifically described without departing from or sacrificing any of the advantages of the invention as defined in the appendent claims.

I claim:

1. In combination with a furnace having a draft and a damper door, a cylinder communicating with a variable pressure source, 55 a piston mounted for reciprocation therein, a piston rod thereon, said piston being arranged to move in response to a pressure change, an adjustable support adjacent said cylinder, a lever pivotally mounted on said support and operatively associated with said

piston rod, a calibrated element mounted on said support adjacent the said lever and rotatable about the same axis as said lever and relative thereto, means carried by said lever at one end thereof for detachably and 70 adjustably connecting it to the said calibrated means, and mechanism for operatively connecting said calibrated means with said doors whereby a pressure change will effect a different setting of said doors. 75

2. In a regulator the combination with a variable pressure source, of an adjustably mounted pivot, a lever mounted on said pivot intermediate the ends thereof, means responsive to a pressure change for imparting movement to said lever, a quadrant lever mounted on said pivot adjacent said first mentioned lever and capable of rotation relative to said first mentioned lever, a flexible body connecting one end of said quadrant with the draft door of a furnace, a second flexible body connecting the other end of said quadrant with the damper door of a furnace, and yielding means carried by the lever for detachably connecting it to said quadrant to cause them to move in unison through a limited operative range. 80

3. In a regulator adapted to operate the damper and draft doors of a furnace, a cylinder adapted to communicate with a variable pressure source, a reciprocating piston in said cylinder arranged to move in response to a pressure change, a piston rod on said piston, a lever operatively associated with said piston rod, a calibrated quadrant lever having notches on its internal peripheral surface mounted adjacent said lever and oscillatable about the same axis as said lever and relative thereto, means for connecting said calibrated quadrant with said doors, and a resiliently mounted pawl on said lever for selectively engaging said notches for regulating the critical pressure at which the lever responds. 100

4. In a regulator the combination of a cylinder adapted to communicate with a variable pressure source, a piston mounted for reciprocation therein, said piston being arranged to move in response to a pressure change, an end connection on said piston rod, an anti-friction element carried by said end connection, a lever having one end thereof operatively associated with said anti-friction element, an adjustably mounted support for said lever, a calibrated element mounted on said support adjacent said lever and adapted for rotation about the same axis as said lever and relative thereto, flexible means for connecting said calibrated element with the draft and damper doors of a furnace, and means for detachably and adjustably connecting the said lever to the said calibrated element whereby the two may be moved in unison along a predetermined path. 115

5. An adjusting device for pressure regu- 120

lated dampers of steam boilers, consisting of a calibrated quadrant lever revolvably mounted upon a pressure actuated lever of the boiler, said quadrant being rotatable about the same axis as said lever and relative thereto, flexible members adapted to connect the ends of said quadrant lever with the dampers of said furnace, and means for de-

tachably retaining said quadrant in any pre-determined position of revolution upon its axis.

In testimony whereof I affix my signature at 10 South La Salle Street, Chicago, Illinois.

BARNEY GOODMAN.
